CLAIM

The ornamental design for a mobile phone holder with magnetic suction ring as shown and described.

DESCRIPTION

FIG. 1 is a front, left, and top perspective view of a mobile phone holder with magnetic suction ring, showing my new design;

FIG. 2 is a rear, right, and bottom perspective view thereof;

FIG. 3 is a front view thereof;

FIG. 4 is a rear view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a perspective view of the mobile phone holder with magnetic suction ring in a first configuration of use; and,

FIG. 10 is a perspective view of the mobile phone holder with magnetic suction ring in a second configuration of use. The broken lines depict portions of the mobile phone holder with magnetic suction ring that form no part of the claimed design.

1 Claim, 10 Drawing Sheets
